UNITED STATES PATENT OFFICE.

PETER J. A. SCHNOOR, OF HOLSTEIN, IOWA, ASSIGNOR OF ONE-HALF TO BUEL COUCH,
OF SIOUX CITY, IOWA.

MOISTENER FOR HOT-AIR FLUES FOR HOT-AIR FURNACES.

1,408,404.

Specification of Letters Patent. Patented Feb. 28, 1922.

Application filed March 29, 1920. Serial No. 369,509.

To all whom it may concern:

Be it known that I, PETER J. A. SCHNOOR, a citizen of the United States, residing at Holstein, in the county of Ida and State of Iowa, have invented certain new and useful Improvements in Moisteners for Hot-Air Flues for Hot-Air Furnaces, of which the following is a specification, reference being had to the accompanying drawings.

10 This invention relates to an improved air moistener for hot air flues of hot air furnaces, and an object of the invention resides in a moistener consisting of a receptacle for the reception of water and adapted to be supported in the hot air flue at a point flush with the floor, and so adjacent the register of the room, as to permit the air to pass over the moistener and collect moisture from the water in the receptacle in order to 15 moisten the air as it enters the room.

Another object is the provision of means for positioning the moistener adjacent the register and substantially flush with the flooring to permit the water to be poured 20 into the receptacle and to permit of the easy insertion and removal of the receptacle.

A further object is to provide a moistener comprising a receptacle having a curved 25 flange acting to direct the hot air from the flue through the register and as it is directed to permit it to gather the moisture from the water. Furthermore, this curved flange performs the function of catching all 30 the dust that may pass down the flue from the interior of the room, that is to say, through the register.

Still another object consists in the provision of supporting means or legs on the 35 receptacle to support the same in position in the flue, and also the provision of a flange to engage the flooring, to further assist in supporting the moistener. The legs or supports frictionally and yieldably engage the opposite side walls of the flue in 40 order to support the moistener receptacle in place.

While the design and construction at present illustrated and set forth is deemed preferable, it is obvious that as a result of a reduction of the invention to a more practical form for commercial purposes, the invention may be susceptible to changes, and the right to these changes is claimed, pro-

vided they are comprehended within the scope of what is claimed.

The invention comprises further features and combination of parts, as will be herein-after set forth, shown in the drawings and claimed.

In the drawings:

Figure 1 is a sectional view through the lower part of the first floor room of a house, showing the hot air flue from the furnace, which is located in the cellar and illustrating the moistener supported in the flue.

Figure 2 is an enlarged detail perspective view of the moisture receptacle; and

Figure 3 is a detail longitudinal sectional view through the moisture receptacle on line 70 3—3 of Figure 2.

Referring to these drawings, 1 designates a hot air furnace which may be any conventional form of construction and has a hot air flue 2 extending therefrom. This flue 75 2 engages the usual hot air flue 3 formed in the wall of the building so that the hot air can pass upwardly into the rooms above the cellar. In order to permit the hot air to enter the room above the cellar, a conventional form of hot air register 4 is provided, and 5 denotes a shutter or closure pivoted at 6 adapted for closing the register, this shutter being capable of being moved to a closed position by means of the handle 7 85 shown in dotted lines. When the shutter is closed, the hot air from the flue 3 is prevented from entering the room. However, when the shutter is open as shown in Figure 1, it acts as a deflector to direct the hot air 90 through the register.

Arranged in the flue is the moisture receptacle 8, which may be any suitable shape, preferably rectangular, and tapering in vertical cross section. This receptacle may be 95 constructed of any suitable material, preferably galvanized iron or the like, and one of its longitudinal edges is provided with a right angular flange 9 to engage in any suitable manner, the floor of the room, whereby 100 assisting in supporting the receptacle in position. The opposite longitudinal edge portion of the moisture receptacle has a flange 10 curved in the direction shown toward the register thereby acting to direct 105 the hot air as indicated by the arrows into the room through the register. This curved flange 10 also performs the function of tak-

ing the dust, dirt and the like from the room through the register and directing it into the receptacle. It is obvious that the shutter 5 may be adjusted in different positions, thereby regulating the quantity of hot air 10 to enter the room. The upper transverse end edges of the receptacle have connected thereto integrally, downwardly and laterally extending flanges or legs 11, which are designed to yieldably bear upon or engage with the side walls of the flue 3 to assist in supporting the receptacle in position. These flanges or legs have their longitudinal portions provided with bent parts 12, curved in 15 cross section, acting to reinforce the legs or flanges 11. When it is desired to refill the receptacle, the register which is capable of being removed, though the structure for this purpose is not shown, is detached, and water 20 poured into the receptacle or the receptacle removed, cleaned and replaced with the same filled with water. The shutter is then adjusted for directing the hot air over the receptacle and through the register accordingly as may be desired.

While it has been stated that the legs or flanges 11 may be used to yieldably bear or engage with the side walls of the flue it is equally as well obvious that the moistener 30 may be supported by other suitable means such as nails or the like, as indicated at 8^a. In this case, the nails 8^a are designed to engage under the flanges or legs 11 at the point where they are bent from the moistener, as 35 shown clearly in Figure 1, thereby permitting the moistener to be easily removed and applied whenever desired. It is also obvious that the lower edges of the legs may bear upon shoulders (not shown) or the lower 40 edges may engage nails that may be driven into the sides of the flue in order to support the moistener.

Further it is the aim to construct such moisteners by stamping them out with a die 45 so as to make a more practical article and also in order to reduce the cost of manufacture.

The invention having been set forth, what is claimed as new and useful is:—

- 50 1. In combination with a hot air flue, a water container arranged in the flue with its upper marginal edge flush with the flooring, means for supporting the receptacle in position, one of the longitudinal edges of 55 the receptacle having a curved flange, serving the double function of directing the hot air through the register, and catching the dust from the register and directing it into the receptacle.
- 60 2. The combination with a hot air flue having a register, a water container supported in the flue with its upper marginal portion flush with the flooring, the innermost

longitudinal edge of the receptacle having a curved flange directed toward the register 65 to direct the hot air through the register and to catch and direct the dust from the room through the register into the receptacle.

3. The combination with a hot air flue having a register, water container supported in the flue with its upper marginal portion flush with the flooring, the innermost longitudinal edge of the receptacle having a curved flange directed toward the register 70 to direct the hot air through the register and to catch and direct the dust from the room through the register into the receptacle, and a shutter mounted in the register adjustable relatively to the curved flange 75 for regulating the amount of hot air passing through the register.

4. In combination with a hot air flue having communication with a room, a register mounted in said communication, a water container supported in the flue, the innermost upper edge of the container having a flange curved toward the register to direct the hot air therethrough, and a shutter pivotally mounted in the register adjustably 85 with relation to the flange for regulating the amount of air passing into the room.

5. The combination with a hot air flue having an opening of communication with a room, of a register in said opening of communication, a water container supported in 95 the flue with its upper marginal edge flush with the flooring of the room, the innermost longitudinal edge of the container having a flange curved toward the register to direct the hot air through the register, and a shutter pivotally mounted in the register and being adjustable for regulating the amount 100 of hot air to pass through the register.

6. The combination with a hot air flue having a register, of a water receptacle arranged in the flue with its upper marginal edge flush with the flooring, means engaging the flooring to assist in supporting the receptacle, said receptacle having additional means yieldably engaging the sides of the 110 flue to further assist in supporting the receptacle, the innermost longitudinal upper edge having a flange curved toward the register for directing the hot air through the register.

7. A water receptacle to be positioned in a flue for supplying heated air to a room, having a marginal flange for engagement with the edge of the flooring of the room, and yieldable means at its ends for engagement with the walls of the flue, whereby 120 said receptacle is supported substantially flush with the room flooring.

In testimony whereof I hereunto affix my signature this 17th day of March, 1920.

PETER J. A. SCHNOOR.
